CLAIM

The ornamental design for a cabinet as shown and described.

DESCRIPTION

FIG. 1 is a top perspective view of a cabinet, showing my new design;

FIG. 2 is a top view of the cabinet of FIG. 1;

FIG. 3 is a bottom view of the cabinet of FIG. 1;

FIG. 4 is a front view of the cabinet of FIG. 1;

FIG. 5 is a rear view of the cabinet of FIG. 1;

FIG. 6 is a left side view of the cabinet of FIG. 1; and,

FIG. 7 is a right side view of the cabinet of FIG. 1.

Portions of the cabinet are shown in broken lines. Portions shown in broken lines form no part of the claimed design. The cabinet is shown with symbolic break lines. The appearance of any portion of the article between the break lines forms no part of the claimed design.

1 Claim, 7 Drawing Sheets
